UNITED STATES PATENT OFFICE.

ADAM LOEFFELHOLZ, OF MILWAUKEE, WISCONSIN.

CAR-SEAT LOCK.

SPECIFICATION forming part of Letters Patent No. 254,226, dated February 28, 1882.

Application filed November 22, 1881. (Model.)

To all whom it may concern:

Be it known that I, ADAM LOEFFELHOLZ, of Milwaukee, in the county of Milwaukee, and in the State of Wisconsin, have invented new and useful Improvements in Car-Seat-Back Locks; and I do hereby declare that the following is a full, clear, and exact description thereof.

My invention relates to car-seat-back locks, and will be fully described hereinafter.

10 In the drawings, Figure 1 is a broken section of a seat-arm with lock detached. Fig. 2 is a central longitudinal section of the same with lock attached. Fig. 3 is a perspective view of the inside of my improved lock, and Fig. 4 is a 15 detail.

A is the seat-arm, cast with a countersink, *c*, and circular opening B.

F E is the shell of the lock, having a circular stepped opening to receive the cam-disk H, 20 on the outside of which is cast a hub, G, having a circular aperture in its center for the shank of the key, and slots for the bits of the key. On its reverse side the disk H has cam-projections *d d*, that abut against the rear end of base-plate L.

Just in front of the opening that receives disk H, I provide the shell E F with guides J, rounded on their outside and flat on their faces, and having grooves in their bases to receive 30 the sides of the base-plate L of bolt D; and a slight projection, *l*, on base-plate L, behind the bolt D, acting upon the faces of the guides J, serves to prevent the bolt D from binding as it slides between the guides. The base-plate 35 is retracted by the spring *b*, secured to posts

c c. After all the parts are in place the shell may be secured to the arm by a couple of screws, *a a*.

In putting my locks together and attaching them to their arms no fitting is necessary that requires skill or the use of any other tool than a screw-driver. I first place the base-plate L upon the base of shell E, and slide it into the grooves in guides J far enough to carry its rear shoulders up against the guides. I then 40 insert plate H, and catch the spring *b* over posts *c c*. The spring will draw the plate L back against the cams *d d* and beneath the disk H, and the lock will be ready for the market. Its operation is very simple. When the disk H is 45 turned one of its cams will force the base-plate L and bolt D forward, and when the key is withdrawn the spring *b* will retract it. The guides J, fitting snugly in aperture B, serve to strengthen the hold of the lock upon the arm. 50

What I claim as my invention, and desire to secure by Letters Patent, is—

In a car-seat lock, the combination of the seat-arm, having aperture B and countersink *c*, with the shell E F, cam-disk H G *d d*, and 55 the bolt D, its base-plate, and a retracting-spring, as set forth.

In testimony that I claim the foregoing I have hereunto set my hand this 14th day of November, 1881.

ADAM LOEFFELHOLZ.
